UNITED STATES PATENT OFFICE.

GEORGE E. HELLMICH, OF SEATTLE, WASHINGTON.

TYMPAN-GAGE.

1,066,010.

Specification of Letters Patent.

Patented July 1, 1913.

Application filed February 24, 1912. Serial No. 679,658.

To all whom it may concern:

Be it known that I, GEORGE E. HELLMICH, a citizen of the United States of America, and a resident of the city of Seattle, in the 5 county of King and State of Washington, have invented certain new and useful Improvements in Tympan-Gages, of which the following is a specification.

My invention pertains to an improved 10 device of the above type embodying certain novel provisions whereby it can be mounted on a tympan sheet for adjustment in relatively angular directions and securely fastened in set position.

15 The invention resides in the novel features and combinations of parts as set forth in the following description and succinctly defined in my annexed claims.

With reference to the accompanying 20 drawing wherein like reference characters designate corresponding parts throughout the several views: Figure 1 is a side elevation of the device, with portions broken away, applied to a tympan sheet. Fig. 2 is a 25 plan thereof with portions broken away. Fig. 3 is a front elevation, and Fig. 4 is a perspective thereof.

I provide the gage proper, as 1, with 30 comparatively long and short base parts 3, 2, the former comprising a forwardly projecting extension of a plate 3', secured by in-turned fingers 3'' to the upturned portion 2' of base part 3. Base parts 2 and 3 extend in opposite directions for projection beneath the tympan sheet, as A, of platen B, through respective parallel slots or incisions b provided therein in suitable spaced relation, whereby the device can be adjusted 35 endwise or laterally on the underlying portion of the sheet, as may be desired in setting the gage.

40 Projecting through suitable apertures in plate 3' and upturned portion 2' of gage 1, is a work guard 4 provided with a head 4' fitting snugly but slidably on a guide 5 which is connected adjacent to gage 1 with base part 3 and spaced outwardly therefrom for clearance of said head with respect to the tympan sheet.

45 Provision is made for positively engaging the tympan sheet to secure the gage in set position, the said provision conveniently comprising a jaw 6 overlying base part 3 and hinged to the free end of a resilient support or spring 7, forming a rearward extension of upturned portion 2', and being

adapted to be forced to bend outwardly during closing movement of jaw 6 by angular jaw extensions or heel parts 8 which ride on the tympan sheet over base part 3 and are 50 finally brought to a forwardly inclined position (see Fig. 1) to engage sheet A in proximity to the rear outer slit b. In this connection, it will be observed that jaw 6 is provided with barbs 6' which in the final 55 closing movement of the jaw pierce the tympan sheet and enter suitable apertures or seats 6'', provided in base part 3 for reception of the points of the barbs. The jaw 6, when open, is free from any resilient means 60 tending to close the same owing to the position assumed by the heels or extensions 8.

Having thus described my invention what I claim as new, and desire to secure by Letters Patent of the United States of America, 75 is:—

1. A tympan gage comprising a body having comparatively long and short base parts projecting in relatively opposite directions for insertion in respective slots of the 80 tympan sheet, a guard extending in angular relation to said body, a jaw for engaging the tympan sheet, and means for pivotally connecting the jaw to the body, whereby the jaw when open is free from any resilient 85 means tending to close the same.

2. A gage comprising a base part having a resilient portion bent backwardly upon said base part and spaced therefrom, a jaw pivoted to the resilient portion of said base 90 part for movement toward the latter, and means to lock said jaw from movement, said means being adapted to move beneath the resilient portion of said base part upon the locking of said jaw.

3. A tympan gage comprising a body provided with a base part adapted for insertion in a slot of the tympan sheet, a guard extending in angular relation to said gage body, a resilient part connected with said 100 gage body, a jaw hinged to said last part, means movable with said jaw for exerting pressure against said base part to spring said resilient part, said means moving in an angle of departure from said base part during final closing movement of said jaw.

4. A tympan gage comprising a body consisting of a base part, a guard extending from said base part, a resilient part connected with said base part, a jaw hinged to 110 said last part for movement toward said base part, and provided with barbs pro-

jecting from its face, and means movable with said jaw for exerting pressure against said base part to spring said resilient part, said means moving in an angle of departure from said base part during final closing movement of said jaw.

5. A gage provided with comparatively long and short base parts projecting in opposite directions, a resilient part, a jaw 10 hinged to said resilient part for movement toward said long base part, means movable with said jaw for exerting pressure against said last base part to spring said resilient part, said means moving in an angle of departure from said last base part during final closing movement of said jaw, a guide overlying said long base part, and a guard slid-

ably supported on said guide and extending in angular relation to said gage.

6. A tympan gage comprising a body with 20 a base part for insertion in a slot of the tympan sheet, a jaw for engagement with the tympan sheet, means for pivotally connecting the jaw to said body, and means carried by the jaw and adapted to ride on the tympan sheet directly over the base part for locking said jaw in an operative position.

Signed at Seattle, Washington this 15th day of February 1912.

GEORGE E. HELLMICH.
